UNITED STATES PATENT OFFICE

158,210

COMBINATION POP-UP AND BUN TOASTER

Alfred W. Madl, Chicago, Ill.

Application September 28, 1948, Serial No. 148,805

Term of patent 3½ years

(Cl. D81—10)

To all whom it may concern:

Be it known that I, Alfred W. Madl, a citizen of the United States, residing at Chicago, county of Cook, State of Illinois, have invented a new, original, and ornamental Design for Combination Pop-up and Bun Toaster, of which the following is a specification, reference being had to the accompanying drawing, forming a part thereof.

In the drawing:

Fig. 1 is a perspective view of a combination pop-up and bun toaster, showing my new design in closed position;

Fig. 2 is a similar view thereof with the sides in open position; and

Fig. 3 is an end elevation of Fig. 1.

I claim:

The ornamental design for a combination pop-up and bun toaster, substantially as shown.

ALFRED W. MADL.
